UNITED STATES PATENT OFFICE

GEORGE WILLIAM GRAVES, OF DETROIT, MICHIGAN, ASSIGNOR TO AMERICAN OLYMPIC
ASSOCIATION, OF NEW YORK, N. Y., A NONPROFIT ASSOCIATION

DESIGN FOR AN EMBLEM OR SIMILAR ARTICLE

Application filed June 21, 1932. Serial No. 44,158. Term of patent 14 years.

To all whom it may concern:

Be it known that I, GEORGE WILLIAM GRAVES, a citizen of the United States, residing at Detroit, in the county of Wayne and State of Michigan, have invented a new, original, and ornamental Design for an Emblem or Similar Article, of which the following is a specification, reference being had to the accompanying drawing, forming part thereof.

The figure is a front view of an emblem or similar article, showing my new design.

The article is of no appreciable thickness.

I claim:

The ornamental design for an emblem or similar article, as shown and described.

In testimony whereof I affix my signature.

GEORGE WILLIAM GRAVES.
